UNITED STATES PATENT OFFICE.

WILHELM LORENZ, OF CARLSRUHE, BADEN, GERMANY.

EXTRACTOR MECHANISM FOR BREECH-LOADING GUNS.

SPECIFICATION forming part of Letters Patent No. 378,169, dated February 21, 1888.

Application filed July 14, 1887. Serial No. 244,271. (No model.)

To all whom it may concern:

Be it known that I, WILHELM LORENZ, of Carlsruhe, in the Grand Duchy of Baden, Germany, have invented a certain new and 5 useful Improvement in Extractors for Metal Cartridge-Cases in Breech-Loading Guns, of which the following is a specification.

The accompanying drawings form a part of this specification and represent means for carrying out the invention with modifications.

Figures 1, 2, and 3 are central horizontal sections through the rear portion of a gun constructed according to my invention. Fig. 1 shows the breech-block being inserted. Fig. 15 2 shows the parts in position for firing, and Fig. 3 shows the ejector in act of throwing out a shell by the quick movement of the ejector-flap. The remaining figures show modifications. Fig. 4 is a horizontal section showing 20 the parts in the position for firing. Fig. 5 is a corresponding section showing the parts in the position for ejecting the shell. Fig. 6 is a rear view of the breech-block, sometimes termed the "breech-wedge," detached. Fig. 25 6^a is a cross-section through a portion of the breech-block in the plane of the firing-pin. Fig. 7 is a cross-section through the gun in the plane of the front of the breech-block. Fig. 8 shows two views of the ejector-flap detached. Fig. 30 9 shows two views of one of the latches detached. These last seven figures belong together and represent similar parts. The succeeding figures show further modifications. Fig. 10 is a central horizontal section showing 35 sliding bolts in place of the latches before shown to operate the ejector-flap. Fig. 10^a shows two views of the said bolts detached. Fig. 11 is a partial horizontal section showing a modification of the hinge of the ejector-flap, and Fig. 12 is a partial horizontal section.

Similar letters of reference indicate corresponding parts in all the figures where they occur.

The arrows indicating motions may be differently marked in the several figures.

In all the figures the extractor A is a flat lever or flap having a semicircular recess which engages the cartridge-case C by matching under its base-rim c. The flap is provided 50 on one face with a rounded lip, a, extending in a straight line across the outer end, which lip engages in a corresponding groove in the

gun D, with liberty to turn thereon. The other face of the flap at that end is formed with stout 55 projections or noses a² a². This flap A is so embedded in a corresponding recess in the front side of the breech-hole that the noses a² a² project into the hole.

Referring to Figs. 1, 2, 3, and 4, latches d d are mounted in the breech-wedge B, one at 60 each side, pressed forward by springs d'. At the withdrawing of the breech-wedge B by moving it in the direction of arrow I the latches d d strike against noses a² a², and thereby turn the extractor-flap A with a short quick 65 turning motion around its collar a as a center. Thereby the cartridge-case C will be thrown backward with a short jerk and ejected. The latches d d are arranged in such position relatively to cartridge-hole B' that the latter is 70 at that time in line with the bore of the gun, so as to permit the cartridge-shell to pass through. The springs d' d' force outward the latches d d; but they will by yielding permit the easy passage of the breech-wedge inward 75 when it has, as is sometimes required, been drawn wholly out of the gun.

B² are shoulders in the breech-wedge extending parallel to the rear face thereof. They act against corresponding smooth surfaces in 80 the gun D, and serve as guides for the breech-wedge in its opening and closing motion, compelling it to traverse in a line parallel to the rear face of the breech-wedge. This insures a clear space for the ejector to move in when the 85 breech-wedge is withdrawn.

The lip a of the extractor-flap is preferably embedded, as shown in Fig. 11, in a rabbet at the surface, and secured thereto by the supporting-plate f and screws f'; or the extractor 90 may be additionally connected by hinges, as shown in Figs. 1, 2, and 3, and in Fig. 12, which will form a pivot for the same. In these latter cases, in order that the breech-wedge may, if required, be conveniently drawn out, 95 the extractor is made removable in the direction of arrow I by the unscrewing and removal of the plate f. In this form of the invention the grooves on the breech-wedge need not extend through, and the rigid shoulders g g on 100 the breech-wedge may push against the noses a² a² for ejecting the cartridge-cases.

In order to allow the pushing backward and forward of breech-wedge B, the same is pro-

vided with grooves of corresponding form and depth.

Further modifications may be made in the shapes and positions of latches d d , bolts e e ,
5 springs d' d' or e' e' , and noses a' a' , or their equivalents, without departing from the principle or sacrificing the advantages of the invention.

I claim as my invention—

- 10 In a breech-loading gun, the gun D, having a rabbet at the outer edge of the breech-block opening, the ejector A, adapted to engage at its front edge under the rim c of the cartridge-shell C, said ejector having a lip embedded in said recess, whereon the ejector

turns pivotally, and also having upwardly extending noses a' , the plate f , and screws f' , removably securing said plate to the gun over said rabbet, for the purpose set forth, in combination with the breech-block B, having 20 shoulders adapted to strike said noses when it is withdrawn, substantially as specified.

In testimony that I claim the foregoing as my invention I have signed my name in presence of two subscribing witnesses.

WILHELM LORENZ.
